UNITED STATES PATENT OFFICE.

THOMAS N. DELIGIANES AND ANDREAS A. BOURDES, OF CHICAGO, ILLINOIS, ASSIGNEES, BY MESNE ASSIGNMENTS, TO GEORGE D. ANTHOULIS, OF GARY, INDIANA.

DISCHARGING MECHANISM FOR PAPER-FOLDING MACHINES.

Application filed May 4, 1923. Serial No. 636,613.

This invention relates to paper folding machines and more particularly to a discharging mechanism for discharging the folded papers from the machine, and an object of the invention is to provide a discharging mechanism as specified which will discharge the papers in upright flat engagement one with another and will prevent tilting, falling or rumpling of the folded 10 papers.

Another object of the invention is to provide a discharging mechanism which comprises means for preventing the last folded paper discharged from interfering with the 15 discharge of the succeeding folded papers.

Another object of this invention is to provide a counting mechanism for automatically counting a pre-determined number of the folded papers and moving the last paper of 20 each pre-determined number into staggered relation relative to the remaining folded papers, to facilitate the binding of the folded papers in packages containing a pre-determined number of the folded papers.

Another object of this invention is to provide a discharging and counting mechanism which is applicable for use upon the napkin folding machines as disclosed in the applications on napkin machines, filed April 4, 1922, 25 Serial No. 549,534 and September 22, 1922, Serial No. 589,834.

Other objects of the invention will appear in the following detailed description taken in connection with the accompanying drawings wherein:—

Fig. 1 is a view in side elevation showing parts in section, of the discharging mechanism.

Fig. 2 is a vertical section on the line 40 2—2 of Fig. 1.

Fig. 3 is a vertical section on the line 3—3 of Fig. 1.

Fig. 4 is a vertical section on the line 4—4 of Fig. 1.

Fig. 5 is a vertical section on the line 45 5—5 of Fig. 4.

Fig. 6 is a vertical section on the line 6—6 of Fig. 2 showing parts broken away.

Fig. 7 is an enlarged detail, partly in side 50 elevation and partly in section of the counting mechanism.

Fig. 8 is a detail section on the line 8—8 of Fig. 7.

Referring more particularly to the drawings, the improved discharging and count-

ing mechanism is particularly designed for use in connection with any suitable type of paper folding mechanism, and the paper is received in the discharging mechanism from the cutters which may be of any approved construction, but which in the present invention comprise knife carrying rollers. The cutting rollers 1, cut the folded paper into proper lengths, and the cut and folded paper is discharged from the rollers 1, into 60 a trough 2 in an edgewise manner and as each individual folded paper is deposited into the trough 2 it is moved outwardly therein by the follower 3. The follower 3 is carried by a sliding bar 5 which is in turn 65 slidably supported by suitable bearings 6. The bar 5 is connected by means of a pivoted operating rod 7 to an eccentric 8 which is rotated by rotation of a shaft 9. The shaft 9 may be rotated from any suitable power 70 source and the proportion and the eccentric of the speed of rotation of the shaft is such that the follower 3 will be moved forwardly at the proper time to force the folded cut paper outwardly in the trough 2, as it is delivered from the rollers 1.

The follower 3 is provided with transversely extending slots 11 extending therein from one side which are adapted to receive the supporting arms 12 of the support 13. The support 13 comprises, the vertical bar 14 which carries the horizontal or transverse arms 12 and a cam roller 15 is carried by the lower end of the bar 14 and engages the cam edge 16 of the cam 17. A sliding bar 18 is 75 connected to the vertical bar 14 and it slides in a suitable slideway 19 beneath the trough 2. A spring 20 is connected to the slide bar 18 and is tensioned to move the arms 12 inwardly through suitable openings 21 in the trough 2, and behind a folded cut piece of paper as it is forced outwardly by the follower 3 so as to prevent the folded paper from falling backwardly when the follower 3 recedes for forcing the next cut piece of 80 paper outwardly. The arms 12 are forced out of the trough 2 and out of the path of the folded piece of paper, upon the forward movement of the follower 3, by the engagement of the cam roller 15 with the cam surfaces 16 which cam surface is cut to perform this function.

A counter structure is provided for counting the cut and folded pieces of paper delivered to the trough 2 and it comprises a 85 100 105 110

vertically movable bar 23 which has a cross head 24 upon its upper end. The cross head 24 is recessed longitudinally as shown at 25 to engage and receive one of the folded 5 pieces of paper. The bottom 26 of the trough 2 is provided with a recess 27 into which the cross head 24 normally rests. The bar 23 is pivotally connected as shown at 28 to an angle bar 29 which is in turn connected to a slide 30. The slide 30 is slidably mounted upon the bar 31 and it has a rack 32 formed on one face thereof, the teeth of which are adapted to be engaged by the tooth 33 of the gear 35 for moving the slide 30 10 upwardly upon engagement of the tooth 33 with the rack 32. It will be noted that the gear 35 has only a single tooth 33, but it is to be understood that it may be provided with two or more teeth at proper spaced 15 relation, if desired and depending upon the frequency at which it is desired to move the counting bar 23 upwardly.

The counting bar 23, will move in an arc, on its pivot 28 on angle bar 29 which movement is necessary owing to the fact that the paper engaged by the head 24 will be moved along the trough 2 during the time that it is engaged by the head. The upward movement of the bar 23 will force the folded cut 20 piece of paper which is engaged by the head 24 upwardly disposing its upper edge above the upper edges of the remaining folded pieces of paper thereby clearly distinguishing it, and by regulating the speed of operation 25 of the gear 35 relative to the speed of delivery of the folded pieces of paper to the troughs 2, it will be noted that any pre-determined number of folded cut pieces of paper may be permitted to pass along the trough 30 2 before the counting bar 23 operates. The trough 2 is relatively long and a relatively large number of the folded cut pieces of paper accumulate therein and it is to be understood that the folded cut pieces of 35 paper may be taken from the trough and bound into any suitable type of bundles and that the forcing upwardly of one of the papers after the passing of a pre-determined number of them over or beyond the bar 23 will permit definite accurate mechanical counting of the folded cut pieces of paper. The bar 23 is returned to its normal downward position by a spring 36, while a spring 37 is provided for returning the slide 30 to 40 its normal downward position. The return of the bar 23 to its normally downward position is guided by movement of a suitable guiding tongue 38 which is carried by the bottom of the tongue 2 and extends into the slot 39 through which the bar 23 extends. The shaft 40 on which the gear 35 is mounted, is operatively connected by means of a worm gear 41 and a suitable worm 42 to a shaft 43 which shaft is driven from the 45 shaft 9 by means of any suitable power

transmitting means 44. The ratio of the worm 42 and worm gear 41 will regulate the speed of rotation of the gear 35 and consequently regulate the intervals of operation of the counting bar 23.

From the foregoing description taken in connection with the accompanying drawings it will be apparent that a mechanism has been provided by means of which cut and folded pieces of paper may be discharged from any suitable type of folding and cutting mechanism, in an effectively easily handled manner, and in such manner as to prevent interference of one piece of paper with the successive discharging of other cut and folded pieces, and also that a mechanism has been provided to accurately and mechanically count the discharged folded and cut pieces of paper.

In Figs. 1 and 2 of the drawings a mechanism is shown for adjusting one of the cutting rollers 1 relative to the other, and this mechanism comprises a feed screw 50 carried by the supporting frame 51 of the mechanism and connected to the bearing box 52 in which the shaft 9 rotates to permit limited adjustment of one of the rollers 1 relative to the other.

It is, of course, to be understood that the invention may be constructed in other manners and the parts associated in different relations and, therefore, we do not desire to be limited in any manner except as set forth in the claims hereunto appended.

Having thus described our invention what we claim is:—

1. In combination, a receiving trough for receiving folded cut sheets of paper, a follower for forcing the paper through the trough, means for operating said follower, a plurality of fingers movable transversely of the trough for engaging and supporting the folded sheets of paper delivered to the trough in upright position upon rescinding movement of the follower, and means for moving said fingers from said supporting position, said last mentioned means including a driven shaft, a cam carried by the shaft and operable therewith, a member movable toward the trough and supporting the fingers, a head formed on one end portion of the member and operable by the cam for moving the fingers from said supporting position, and means for moving said member and head in an opposite direction to dispose the fingers in said supporting position.

2. In combination, a receiving trough for receiving folded cut sheets of paper, means for forcing the paper through the trough, means for operating said forcing means, means movable transversely of the trough in substantially horizontal plane for engaging and supporting the folded sheets of paper delivered to the trough in an upright posi-

tion upon rescinding movement of the follower, and means for moving said supporting means, said last mentioned means including a member carrying said supporting means and movable relatively to the trough within a guideway beneath a trough, cam acting means operating on an element of said supporting means for moving said supporting means and said member in one direction and means for moving said supporting means and said member in an opposite direction.

3. In combination, a receiving trough for receiving folded sheets of paper, a follower for forcing the paper through the trough, means for operating said follower, a counting bar movable into the trough for individual engagement with the sheets being forced through the trough by the follower, means for operating said follower, and means operable by said follower operating means for operating said counting bar, said last mentioned means including a movable

rack, and a pivotal connection between the rack and the counting bar.

4. In combination, a receiving trough for receiving folded sheets of paper, a follower for forcing the paper through the trough, means for operating said follower, a counting bar movable into the trough for individual engagement with the sheets being forced through the trough by the follower, means for operating said follower, means operable by said follower operating means for operating said counting bar, said last mentioned means including a movable rack, a pivotal connection between the rack and the bar, and means movable into the trough for engaging and supporting the sheets in an upright position upon rescinding movement of the follower and during operation of the counting bar upon the sheets.

In testimony whereof we affix our signatures.

THOMAS N. DELIGIANES.
ANDREAS A. BOURDES.
